HARMONICA RING

Christy M. Del Mas, New York, N. Y., assignor to Michael P. Grace, New York, N. Y.

Application May 4, 1953, Serial No. 24,834

Term of patent 14 years

(Cl. D45—10)

To all whom it may concern:

Be it known that I, Christy M. Del Mas, a citizen of the United States of America, residing at city, county and State of New York, have invented a new, original, and ornamental Design for a Harmonica Ring, of which the following is a specification, reference being had to the accompanying drawing, forming part thereof.

The figure is a perspective view of a harmonica ring embodying my new design.

The opposite side of the ring is the same as that shown.

I claim:

The ornamental design for a harmonica ring, as shown and described.

CHRISTY M. DEL MAS.
